CABLE JUNCTION JACKET

James J. Johnston, Cheshire, Conn., assignor to Automatic Equipment Development Corporation, West Haven, Conn.

Filed Jan. 19, 1973, Ser. No. 325,087

Term of patent 14 years

Int. Cl. D13—99

U.S. Cl. D26—5 B

FIG. 1

FIG. 2

FIG. 3

FIG. 6

FIG. 7

FIG. 8

FIG. 4

FIG. 5

FIG. 9

FIG. 1 is a side elevational view of a cable junction jacket showing my new design, it being understood that the opposite side is a mirror image thereof.

FIG. 2 is a left end elevational view thereof.

FIG. 3 is a right end elevational view thereof.

FIG. 4 is a plan view thereof.

FIG. 5 is a sectional view thereof taken along the line 5-5 of FIG. 2.

FIG. 6 is a side elevational view of a cable junction jacket showing a second embodiment of my new design, it being understood that the opposite side is a mirror image thereof.

FIG. 7 is a left end elevational view of the cable junction jacket of FIG. 6.

FIG. 8 is a right end elevational view of the cable junction jacket of FIG. 6.

FIG. 9 is a plan view of the cable junction jacket of FIG. 6.

FIG. 10 is a side elevational view of a cable junction jacket showing a third embodiment of my new design, it being understood that the opposite side is a mirror image thereof.

FIG. 11 is a left end elevational view of the cable junction jacket of FIG. 10.

FIG. 12 is a right end elevational view of the cable junction jacket of FIG. 10.

FIG. 13 is a plan view of the cable junction jacket of FIG. 10.

FIG. 14 is a sectional view of the cable junction jacket of FIG. 10 taken along line 14-14 of FIG. 11.

FIG. 15 is a side elevational view of a cable junction jacket showing a fourth embodiment of my new design, it being understood that the opposite side is a mirror image thereof.

FIG. 16 is a left end elevational view of the cable junction jacket of FIG. 15.

FIG. 17 is a right end elevational view of the cable junction jacket of FIG. 15.

FIG. 18 is a plan view of the cable junction jacket of FIG. 15.

I claim:

The ornamental design for a cable junction jacket, as shown and described.
